PENCIL SHARPENER

August W. Quinby, Redding, Calif.

Application March 31, 1936, Serial No. 71,908

3 Claims. (Cl. 120—93)

The invention relates to a pencil sharpener and has for its primary object a sharpener which accommodates a safety razor blade which is held in such a manner that it may be adjusted without removal of the blade to vary the position of the cutting edge in relation to the pencil to be sharpened.

Another object of the invention is the provision of a sharpener of this character, wherein the conical shaped thimble which accommodates the end of the pencil to be sharpened is removably fitted upon a cover to a container for trapping the shavings when the pencil is being sharpened, the sharpener being of novel construction and is unique in accommodating a safety razor blade which is readily renewable at the will of the user of the sharpener.

A further object of the invention is the provision of a sharpener of this character, which is extremely simple in its construction, thoroughly reliable and efficient in its operation, durable, strong, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

30 In the accompanying drawing:

Figure 1 is a top plan view of a sharpener constructed in accordance with the invention.

Figure 2 is a sectional view on the line 2—2 of Figure 1 looking in the direction of the arrows.

35 Figure 3 is a sectional view on the line 3—3 of Figure 2 looking in the direction of the arrows.

Figure 4 is a sectional view on the line 4—4 of Figure 1 looking in the direction of the arrows.

Figure 5 is a sectional view similar to Figure 2 showing a modified form of sharpener.

Figure 6 is a view looking toward the inner face of the lid or cover carrying the sharpener shown in Figure 5.

Similar reference characters indicate corresponding parts throughout the several views in the drawing.

Referring to the drawing in detail, particularly Figures 1 to 4 inclusive, the sharpener comprises a conical shaped member or thimble 10 open at opposite ends and having a slot 11 longitudinally extended therethrough while at one side of this slot 11 is a laterally extending flat wing 12 forming a guard for a safety razor blade 13, its cutting edge 14 being in confronting relation to the slot 11 and extends sufficiently with respect thereto

to function as a cutter for the end of a pencil when the said end of the latter is inserted within the thimble or member 10 for sharpening purposes.

The wing 12 is adapted for detachable connection with the cover 15 of a container 16 preferably of cylindrical form and the latter is adapted to catch shavings during the sharpening operation of the pencil. This lid or cover 15 is formed with a slot 17 companion to the slot 11 of the thimble or conical member 10 so that the shavings will pass through the slot 17 and become deposited within the container 16 when the lid or cover is wearing the sharpener.

Struck outwardly from the lid or cover is a framing bead 18 constituting a seat for the wing 12 and thus in this manner enabling the quick matching of the slots 11 and 17 with each other when the wing 12 is seated upon the lid or cover, a fastener 19 detachably secures the sharpener in place and also adjustably holds the blade 13 located between the wing 12 and the lid or cover 15.

The pencil to be sharpened at the end for sharpening is first inserted into the conical member or thimble 10 then by a twisting action the blade will cut the pencil for the sharpening thereof and the shavings will be deposited in the container 16.

In Figures 5 and 6 of the drawing there is shown a slight modification of the sharpener wherein the lid or cover 20 has an opening 21 accommodating a cameo face 22 formed on the bottom side of the sharpener 23 while at opposite ends and one side of this opening 21 is an instruck bead 24 in the lid or cover 20 and attached by a clamping plate 25 and a fastener 26 to the wing 27 of the sharpener 23 is the safety razor blade 28. The sharpener 23 is made secure in proper position upon the lid or cover 20 by rivets or fasteners 29 thus such lid or cover and the sharpener are unitary or permanently joined with each other.

What is claimed is:

1. A sharpener of the kind described comprising a conical shaped member having a longitudinal slot therein, a lateral wing extending from said member at one side of the slot, a container lid having an opening matching the slot in said member, a safety razor blade detachably fitted with said wing for presenting a cutting edge to the slot in said member, and a seat formed in the lid for said wing and blade.

2. A sharpener of the kind described comprising a conical shaped member having a longitudinal slot therein, a lateral wing extending from

said member at one side of the slot, a container lid having an opening matching the slot in said member, a safety razor blade detachably fitted with said wing for presenting a cutting edge to the slot in said member, a seat formed in the lid for said wing and blade, and means for adjustably clamping the blade with respect to said wing.

3. In combination, a conical shaped member having a longitudinal slot therein, a lateral wing extending from said member at one side of the slot, a cutting blade for detachable fitting with

said wing, a container, a lid for said container having a slot matching the slot in said member, a seat on said lid for guiding said wing and blade into proper position whereby the slots in said member and in said lid are in registry and the cutting edge of the blade is presented to said slots, and means cooperating with said seat for detachably holding the blade and member in proper position.

AUGUST W. QUINBY. 10
